UNITED STATES PATENT OFFICE

151,321

DESIGN FOR AN ELECTRIC IRON

Fred W. Busch, Milwaukee, Wis., assignor to Mil-
steel Products Co., Milwaukee, Wis., a corpora-
tion of Wisconsin

Application October 28, 1946, Serial No. 134,324

Term of patent 14 years

(Cl. D49—6)

To all whom it may concern:

Be it known that I, Fred W. Busch, a citizen of the United States, residing at Milwaukee, in the county of Milwaukee and State of Wisconsin, have invented a new, original, and ornamental Design for an Electric Iron, of which the following is a description, reference being had to the accompanying drawing, forming a part thereof.

In the drawing:

Fig. 1 is a perspective view showing the front, top and one side of an electric iron, embodying my new design;

Fig. 2 is a top view of the iron; and

Fig. 3 is a rear view thereof.

The dominant features of my design reside in the portions shown in full lines.

I claim:

The ornamental design for an electric iron, substantially as shown and described.

FRED W. BUSCH.
